DESIGN FOR A DOILY OR SIMILAR ARTICLE

Kenneth C. Hamilton, Milwaukee, Wis., assignor to Milwaukee Lace Paper Co., Milwaukee, Wis., a corporation of Wisconsin

Application October 17, 1940, Serial No. 95,888

Term of patent 14 years

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily or Similar Article, of which the following is a specification, reference being had to the accompanying drawing, forming a part thereof.

The figure is a plan view of a doily, showing my new design, the same being photographed upon a black background in order to bring out more clearly the details thereof. While my design is shown as delineated on a doily, it is to be understood that the same may be applied to other similar articles without departing from the spirit of the invention.

I claim:

The ornamental design for a doily or similar article, substantially as shown and described.

KENNETH C. HAMILTON.
